UNITED STATES PATENT OFFICE.

EDWARD S. CLARK, OF BOSTON, MASSACHUSETTS.

VALVE-OPERATING DEVICE FOR FLUID-CONDUITS.

1,191,947.

Specification of Letters Patent. Patented July 25, 1916.

Application filed January 2, 1915. Serial No. 287.

To all whom it may concern:

Be it known that I, EDWARD S. CLARK, a citizen of the United States, residing at Boston, in the county of Suffolk and State 5 of Massachusetts, have invented new and useful Improvements in Valve-Operating Devices for Fluid-Conduits, of which the following is a specification.

My invention relates to valve operating devices for fluid conduits; and its objects 10 are to reduce the damage due to breaks and to conserve the supply of fluid, to speedily regulate the volume of fluid, to facilitate the testing of the gates used for opening 15 and closing the conduit, to open and close said gates with the rapidity required in emergencies, to utilize and apply a source of power other than manual means, to make the device adjustable and quickly available 20 for practical use, to stop the operation of the device automatically when the gates are fully open or closed, and to produce a device which is simple and economical in construction and in other ways effective in the relation 25 for which it is designed.

At the present time it is the general custom in the great cities to use for opening and closing large water or gas mains at points of the line where it is deemed desirable, gate valves of heavy construction. In 30 the case of water mains these are ordinarily thirty-six inches in diameter, and are closed by a gate wrench which requires about three hundred turns thereof and the work of four men laboring continuously for about forty-five minutes for its effective operation. Such labor is very severe, and where it is necessary, as often occurs, to close several 35 gates, the efficiency of the men becomes greatly reduced with each successive gate, and if the number of gates is further increased, the men become exhausted and must be given a period of rest perhaps at a time when delay may mean the loss of life or 40 property. This will be readily appreciated if it be borne in mind that in the case of a complete break the escape of the water from a large main would be in the vicinity of fifty thousand gallons a minute, all of which 45 must find some outlet to the damage of property owners in the vicinity. Then again in case of fire, it becomes necessary to act promptly with reference to the gates not only to prevent the waste of water in 50 the fire district through breaks where it is diverted from effective use, but also to allow

the full head of the water to be utilized where it is most needed.

My invention primarily consists in mounting a universal wrench socket, which 60 is made self adjusting, upon a motor vehicle, and, to operatively connect to its source of motive power, mechanism for turning the said wrench socket.

My invention further consists in the various 65 improvements and novel arrangement of parts hereinafter more fully set forth or illustrated in the drawing and referred to in the claims.

Through the use of my invention in connection 70 with a motor truck under the conditions of actual use, I have found that the work of closing the gate valves which formerly occupied so much time, necessitating the labor of a number of men, and limited 75 because of human endurance, can now be accomplished in ten minutes or less by one man alone, and that my device was equal to every emergency and has effectively taken care of work formerly attended to in a necessarily 80 inadequate manner.

Attention is hereby directed to the drawing 85 in which similar numerals of designation refer to similar parts throughout the several views.

Figure 1 is a plan of the frame of the chassis showing the casing of my improved wrench socket and its relation to the main shaft; Fig. 2 is a side elevation of a motor truck to which the turning mechanism of 90 my improved wrench socket is secured; Fig. 3 is a horizontal section of the mechanism and connections adjacent to the main shaft; Fig. 4 is a plan view of the turning mechanism shown partly in section with the upper hemisphere of the casing of the wrench socket removed; Fig. 5 is a vertical section on line 4—4 of the view shown in Fig. 4, looking in the direction of the arrows, and Fig. 6 is a side elevation of the universal 95 joint at the lower end of my wrench.

Referring to the drawing: Upon the chassis frame 7 of the motor truck 8, I mount in any suitable manner the casings 9 and 10 containing the mechanism for turning the wrench 11, the casing 9 being preferably secured to the said frame by means of the brackets 47 and 48, and the casing 10 inclosing a portion of the driving mechanism connected with the main shaft 50, and 110 being preferably secured to said frame by the arms 14 and rigidly connected to the

2

transmission casing 51 by lugs 49 or other suitable means. The portion of the driving mechanism within the casing 10 is made of special construction to meet with the requirements of my invention. (See Fig. 3.) To the square tapering end 12 of the shaft 25 is secured the socket 15 of the rectangular insert 16, which is shaped to register and to revolve therewith. Inclosing the wall of 10 said socket 15 is the collar 17 freely rotating on the ball bearings 18 and held in operative position by suitable means and bearing the bevel gear 19 which is bolted thereto. The inner portion of the collar 17 is 15 constructed in the form of a gear or clutch 20 shaped to engage with the clutch 21, which slides longitudinally upon the rectangular insert 16 and rotates therewith. At 20 the other end of the said insert 16 are the ball bearings 22 installed within the clutch or gear 23 journaled in the ball bearings 24 secured to the main frame, and which clutch 23 is integral and rotates with the square tapering end 13 which is normally affixed 25 to the main shaft 50 in the rearward part of the truck. As will be well understood by persons acquainted with the art, the movement of the clutch 16 well to the left will cause engagement and rotation of the bevel gear 19, while the movement of said clutch well to the right causes the rotation of the 30 said shaft 50.

Mesning with the bevel gear 19 is the bevel gear 26 mounted upon one end of the 35 countershaft 28 which is journaled in the ball bearings 27 mounted upon the casing 10. The remaining portion of said countershaft 28 carries the worm 29 and is journaled in the ball bearings 30^a and 30^b mounted within 40 and upon the housing 32, the ball bearings 31 similarly mounted serving to take up the end thrust of said countershaft. Preferably the extreme end 52 of said portion of said countershaft is made square in order to 45 afford an opportunity for the application and use of a hand wrench if desired. Mesning with said worm 29 is the worm gear 33 which is bolted to the two parts of the sleeve 34 mounted within the casing 9 and rotating 50 upon ball bearings 35. Within the sleeve 34 is the circular frame 36 having at opposite parts of its circumference the bearings 38, which engage with the trunnions 37 firmly secured to the inner portions of said sleeve. 55 In suitable bearings upon said frame 36 are pivotally mounted the spokes 39 of the hub 40. The hub 40 is provided with the socket 41 which is shaped to readily engage with the wrench 11 which is square in cross section and which serves to turn the same. The 60 openings 42 at each mouth of the sleeve, are, it will be observed considerably wider, than the socket 41; the object of which is to allow considerable play of the wrench 11, and to 65 permit the same to adjust itself automatically

to varying conditions. In order to prevent the escape of the lubricating oil used for the bearings within the casing 9, I preferably employ the screw ring 53 which is threaded to engage with the lowest part of 70 the lower hemispheres of said casing, and to hold the packing in place.

Preferably the casing 9 is constructed of hemispheres with wide flanges as shown bolted together at the line of juncture. In 75 order to prevent any strain or breakage of machinery, I prefer to construct the lower part of my improved wrench, containing the jaw 44, with a universal joint 45 provided with a pin 43 of copper, soft iron or other 80 material of a torsional strength somewhat less than the teeth of the gears of my turning mechanism above described (see Fig. 6), so that if by accident the operation is protracted after the gate has been fully opened 85 or closed the pin 43 will break and the further application of the power to the gate will be discontinued. Normally when the wrench is not in use, it is carried in the position shown in Fig. 2, a clamp 46 or any 90 other suitable means being employed for suspending the same.

As is obvious, my device may be adapted and applied for operating any gate, door, valve, plug or other means for stopping the 95 passage of steam, illuminating gas, oil, water or other fluid through a conduit or other aperture, and by the term "wrench valve" as used in the claims, I desire to be understood as including within its scope and 10 meaning any such gate, door, valve, plug or other means employed for such purpose and of such construction as to be susceptible of being actuated through the application of a wrench of the general character above set forth and described.

The operation of my invention is as follows: The motor truck shown in Fig. 2 is driven into such position as to bring the wrench socket directly over the man hole of 11 the gas or water gate which it is desired to open or close; the man hole cover is removed, and the wrench is slipped through the said socket and brought into engagement with the nut on the gate gear below. 11 The clutch 21 is then moved into engagement with the clutch 20 and the bevel gear 19 is caused to rotate, and through the transmission gears above described, to turn the wrench socket 41 and the wrench 11 therein, thereby turning the said nut and opening or closing the gate as desired. Care should preferably be taken, however, that the operation does not proceed so far as to go beyond the complete opening or closing of the 12 gate so as to cause the breaking of the pin 43; and in practice with unskilled workmen I prefer to have them stop somewhat short of this point and to leave the last few turns to be accomplished by a hand wrench ap- 1

plied to the square end 52. But with a skillful operator this practice may be dispensed with, since the gates are ordinarily equipped with indicators showing the position of the 5 valve and informing him when the valve is seated or entirely opened, or where such indicators are not present, the number of revolutions of the wrench may be counted, the number required to close any type of gate 10 being generally known.

What I claim and desire to secure by Letters Patent is,—

1. A device for opening and closing wrench valves, consisting of a vehicle, an 15 adjustable wrench carried thereon, mechanism for turning said wrench secured to said vehicle, and means of propulsion carried by said vehicle and operatively connected to drive the said wrench mechanism.
2. A device for opening and closing 20 wrench valves, consisting of a vehicle, a portable sliding wrench carried thereon, mechanism for turning said wrench secured to said vehicle, and means of propulsion carried by 25 said vehicle and operatively connected to drive said wrench turning mechanism.

3. A device for turning the polygonal stem of wrench valves, consisting of a vehicle, 30 a portable wrench bar one end of which is shaped to engage with said stem and which is carried by said vehicle, mechanism for turning said wrench bar secured to said vehicle, and means of propulsion carried by 35 said vehicle and operatively connected to drive said wrench turning mechanism.

4. A device for opening and closing wrench valves consisting of a motor vehicle, an adjustable wrench and wrench socket 40 therefor mounted upon said vehicle, mechanism secured to said vehicle for turning said socket, said mechanism being operatively connected with the motive power of said vehicle.

45 5. A device for opening and closing wrench valves, consisting of a motor vehicle, a portable sliding wrench carried by said vehicle and adjustable to and from the wrench valve, mechanism secured to said vehicle for turning the said wrench and operatively connected with and driven by the motive mechanism of said vehicle.

6. A device for turning the stem of wrench valves, consisting of a motor vehicle, 55 a portable sliding wrench carried by said vehicle, a universal jaw carried by said wrench and shaped to engage with said stem, mechanism secured to said vehicle for turning said wrench and operatively connected with and driven by the motive power means of said vehicle.

7. A device for turning the stem of wrench valves, consisting of a motor vehicle, a portable sliding wrench carried by said vehicle and adjustable to and from the stem 65 of the wrench valve, a universal jaw carried by said wrench and shaped to engage with said stem, mechanism secured to said vehicle for turning said wrench and operatively connected with and driven by the 70 motive power means of said vehicle.

8. A device for opening and closing wrench valves consisting of a motor vehicle, a universal wrench socket secured to said vehicle, a vertically sliding wrench engaging 75 with said socket, and mechanism for turning said wrench socket operatively connected with the motive power of said vehicle.

9. A device for opening and closing wrench valves consisting of a motor vehicle, 80 a universal wrench socket secured to said vehicle, a vertically sliding wrench engaging with said socket, a universal jaw secured to the end of said wrench, and mechanism for turning said wrench socket operatively 85 connected with the motive power of said vehicle.

10. A device for opening and closing wrench valves for water and gas mains consisting of a motor vehicle, a universal 90 wrench socket secured to said vehicle, a vertically sliding wrench engaging with said socket, a universal jaw secured to the end of said wrench, and mechanism for turning said wrench socket operatively connected 95 with the motive power of said vehicle, the said jaw being secured as aforesaid by a pin of less strength than that of said mechanism.

11. A device for opening and closing wrench valves for water and gas mains, 100 consisting of a motor vehicle, a universal wrench socket secured to said vehicle, a vertically sliding wrench therefor, a worm and a worm gear for turning said socket, and mechanism operatively connecting said 105 worm to the motive power of said vehicle.

12. A device for opening and closing wrench valves for water and gas mains, consisting of a motor vehicle having a driving shaft, a universal wrench socket secured to 110 said vehicle, a worm and worm gear for turning said socket and a bevel gear mounted upon a counter shaft carrying said worm and meshing with a bevel gear mounted upon said driving shaft.

In testimony whereof I have hereunto set my hand in presence of two subscribing witnesses, this 30th day of January, 1914.

EDWARD S. CLARK.
